(57) **CLAIM**

We claim the ornamental design for a boat for substrate processing apparatus, as shown (and described).

DESCRIPTION

FIG. 1 is a front, top and left side perspective view of a boat for substrate processing apparatus showing our new design; FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof.

FIG. 8 is an enlarged portion view take along line 8 in FIG. 2 thereof;

FIG. 9 is a view take along line 9-9 in FIG. 2 thereof;

FIG. 10 is a view take along line 10-10 in FIG. 2 thereof;

FIG. 11 is a perspective view of the claimed portion indicated by the solid line in FIG. 8 thereof;

FIG. 12 is a front elevational view of the claimed portion indicated by the solid line in FIG. 8 thereof;

FIG. 13 is a rear elevational view of the claimed portion indicated by the solid line in FIG. 8 thereof;

FIG. 14 is a right side elevational view of the claimed portion indicated by the solid line in FIG. 8 thereof;

FIG. 15 is a left side elevational view of the claimed portion indicated by the solid line in FIG. 8 thereof;

FIG. 16 is a top plan elevational view of the claimed portion indicated by the solid line in FIG. 8 thereof; and,

FIG. 17 is a bottom plan elevational view of the claimed portion indicated by the solid line in FIG. 8.

The broken lines show portions of a boat for substrate processing apparatus that form no part of the claimed design.

The “dash-dot” broken line in FIG. 2 represents the bounds of the enlarged portion of the claimed design in FIG. 8

The “dash-dot” broken line in FIG. 2 also show the plan view from which FIGS. 9 and 10 are taken.
